Specification for Design.

Patented Aug. 1, 1916.

Application filed January 29, 1915. Serial No. 5,155. Term of patent 7 years.

To all whom it may concern:

Be it known that I, CLARENCE W. LUCAS, a citizen of the United States, residing at Decatur, in the county of Mason and State of Illinois, have invented a new, original, and ornamental Design for a Ventilated Shade-Holder, of which the following is a specification, reference being had to the accompanying drawing, forming part thereof.

The figure is a side elevation of a ventilated shade holder, showing my new design.

I claim:

The ornamental design for a ventilated shade holder, as shown.

CLARENCE W. LUCAS.
